UNITED STATES PATENT OFFICE

136,618

DESIGN FOR A JACKET

Morris Seidman, New York, N. Y.

Application October 5, 1943, Serial No. 111,270

Term of patent 3½ years

To all whom it may concern:

Be it known that I, Morris Seidman, a citizen of the United States, residing at New York, in the county of Bronx and State of New York, have invented a new, original, and ornamental Design for a Jacket, of which the following is a specification, reference being had to the accompanying drawing, forming part thereof.

I claim:

The ornamental design for a jacket, as shown.

MORRIS SEIDMAN.
